UNITED STATES PATENT OFFICE

2,392,324

LAMP SHADE

Ernest Krebeck, Washington, D. C.

Application April 28, 1944, Serial No. 533,174

1 Claim. (Cl. 240—108)

The invention relates to a lamp shade, and more especially to a collapsible lamp shade.

The primary object of the invention is the provision of a shade of this character, wherein the same when extended for use will retain its shape, through the use of expandable hoops, these being removable from the body of such shade, so that the said body can be cleaned or laundered, and when the shade is removed from its support it can be collapsed, thereby enabling the same to be stored in the least possible space, or when being transported from one place to another, and particularly when packaging a number thereof for transit in merchandising the same.

Another object of the invention is the provision of a shade of this character, wherein on the setting up of the same it will retain proper shape, to give a neat and pleasing appearance thereto when in use, and by reason of its flexibility there is less liability of damage thereto through accidental contact therewith while in use, as the body of such shade will not tear or become broken as is generally the case with shades having rigidly formed bodies or skirts, the shade being readily and easily hung in place on a support, and can be conveniently detached from the latter for the collapsing of the same.

A further object of the invention is the provision of a shade of this character, wherein it possesses all of the ornamental characteristics of the standard rigid types of shades for lamps, and is retained in shape by the resilient or expandable hoops, thereby dispensing with the fixed frame formation generally employed for this purpose.

A still further object of the invention is the provision of a shade of this character, wherein its body can be readily and easily removed at will, to enable it to be collapsed for the cleansing thereof in a speedy and convenient manner, and then replaced on a lamp for further use, or the substituting of another shade body of a different design or texture, the shade in its entirety being of novel and unique construction, and is assured of maximum wear and life thereto, and is devoid of a frame mounting of any description in the use thereof.

A still further object of the invention is the provision of a shade of this character, which is extremely simple in construction, thoroughly reliable and efficient for the purposes intended thereof, strong, durable, neat and attractive in appearance, possessed of few parts, and inexpensive to manufacture and install.

With these and other objects in view the in-

vention consists in the features of construction, combination and arrangement of parts as will be hereinafter more fully described, illustrated in the accompanying drawing, which shows the preferred embodiment of the invention, and pointed out in the claim hereunto appended.

In the accompanying drawing:

Figure 1 is a side elevation, partly broken away, of a shade constructed in accordance with the invention, and in position for use on a lamp fixture.

Figure 2 is a top plan view thereof.

Figure 3 is a perspective view of one of the expandable hoops employed with the body of the shade, and removed from the latter.

Figure 4 is a fragmentary side view, partly in section of a modified form of hanger for the shade.

Similar reference characters indicate corresponding parts throughout the several views in the drawing.

Referring to the drawing in detail A designates generally a collapsible lamp shade constructed in accordance with the invention, and B denotes one form of support or hanger for the shade.

The shade A comprises, in this instance, a truncated conical shaped endless body 10, preferably made from any suitable flexible material, having transparency for light penetration, and is entirely devoid of a lining. The body 10 may be of any other formation than conical shape, if found desirable, and may bear ornamentation of any kind. In this instance, the body 10 is smooth, yet it may be pleated or crinkled within a definite area thereof. The body 10 is preferably made from textile material, but it may be made from any other fibrous substance if desired.

Formed at the upper and lower open ends of the body 10 are endless casements 11 and 12, respectively, these being preferably provided at the inner face of the said body, and each is provided with a clearance opening 13, for communication with the interior of the casement, so that a split expandable band, hoop or the like 14 can be removably inserted within the latter, this band, hoop or the like being best seen in Figure 3 of the drawing. The band, hoop or the like 14 is preferably made from plastic material, and can be flat faced, round, or otherwise contoured. The bands, hoops or the like 14 when threaded into the casements 11 and 12, through their inherent expansibility, will give shape to the body 10, and retain it in a taut condition.

The weight of the band, hoop or the like 14 in the lower casement 12 tends to keep the body

18 stretched, when the upper end of the latter, with the casement 11, and the band, hoop or the like therein, is engaged on the support or hanger B, so that overall, the said body is retained in proper shapely condition during use thereof on a lamp.

Now, it is to be understood, that the casements 11 and 12, can be altered so that they may create runs of eyelets for the bands, hoops or the like 14, and on removal of the body 10 from the support or hanger B, the same becomes collapsed, then by removing the bands, hoops or the like from the casements 11 and 12, the said body 10 can be readily and conveniently cleaned or laundered, in any selected manner, as are articles of wearing apparel.

The support or hanger B is mounted on a vertical fixture of any standard construction forming the equipment of a lamp, not shown. The hanger or support B is provided with radial arms 15, having terminal hooks 16, for the engagement of the upper end of the body 10 of the shade A therewith, so that the latter will hang therefrom in the usual manner, the body 10 being entirely devoid of a supporting frame and permanent attachment thereto, common in present day lamp shade manufacture.

To give a reasonable amount of stiffness to the body 10, it may be starched or otherwise treated in the laundering thereof, if desired.

In Figure 4 of the drawing, there is shown a slight alteration in the support or hanger for the shade, wherein each arm 17 is sectionally extensible or contractible as at 18 and 19, respectively, so that such support or hanger can be varied in size.

The casement 11 and particularly the casement 12 may be formed removed from the ends of the body 10, and by this arrangement of the said casement 12, the lower edge portion of the shade will be in the form of a skirt to the body, and this edge portion constitute a fringe area, the ends of the body being varied to suit different conditions and tastes.

5 The shade A when removed from its support or hanger B becomes collapsed, so that it can be stored in the least possible space while not in use, and also renders the same more handy for compactness in shipment, and by the removal of the bands, hoops or the like 14 from the casements 11 and 12, the body 10 of the said shade will be in condition for cleaning or laundering.

10 The support or hanger B is provided with a center bearing 20 for the attachment thereof to a vertical post of a lamp fixture, as is commonly done with standard makes of shades.

15 From the foregoing it is thought that the construction and manner of operation of the shade will be clearly understood, and therefore, a more extended explanation has been omitted, for the sake of brevity.

20 Further, it is to be understood that changes, variations and modifications may be made in the invention as fall properly within the scope of the claim hereunto annexed without departing from the spirit of the invention or sacrificing any of its advantages.

25 What is claimed is:

30 A lamp shade of the kind described, comprising an endless substantially circular shaped flexible body having open top and bottom end areas, split expandible ring-like members correspondingly shaped to the circular contour of the body, casements provided on the body at the top and bottom ends and each having a clearance opening for quick insertion and removal of the split-ring like members in and from the casements, the ring-like members when inserted in the casements being effective for extending the body in a lateral taut condition to the vertical axis thereof, and a hanger having terminal hooks for detachably engaging the upper end of the body for suspending its open top to have the open bottom 35 area pendent and weighted by the ring-like member at this area to effect such body taut between such area and the hanger.

40 ERNEST KREBECK.
